United States Patent Office.

JAMES J. CRISPIN, OF PROVIDENCE, RHODE ISLAND.

Letters Patent No. 71,584, dated December 3, 1867.

IMPROVEMENT IN EYE-GLASSES.

The Schedule referred to in these Letters Patent and making part of the same.

TO ALL WHOM IT MAY CONCERN:

Be it known that I, JAMES J. CRISPIN, of Providence, in the county of Providence, and State of Rhode Island, have invented an Improvement in Hand-Spectacle Frames; and do hereby declare that the following is a full and exact description, reference being had to the accompanying drawings, making a part of this specification.

The nature of my invention consists in an improved method of attaching the bow or bend of the spring to the eye-glass frames, and also in the use of a spiral spring as a portion of such connection.

To enable those skilled in the art to make and use my invention, I will proceed to describe its construction and operation.

Figures 1 and 2 show the means adopted for securing the bow of the spring A to the eye-glass frames B B'. The clasp C is made of a piece of metal having its edges forced down over the edges of the spring, so as to hold it firmly. In connecting this clasp to the frames B B', I use either a solid or rigid connection, shown at D, or a spiral spring, shown at E.

The object of this improvement is to furnish a means of securing a connection to the spring A at the point indicated, without weakening such spring by a rivet-hole or screw, as heretofore used in the manufacture of such frames. The use of the spiral spring E allows the spring A a greater extent of motion.

What I claim as my invention, and desire to secure by Letters Patent, is—

The combination of a clasp, C, spring A, and frame B, substantially as described.

I also claim the combination of the spring A, spiral spring E, and frame B, substantially as described.
